UNITED STATES PATENT OFFICE.

HUGO F. BRUGMANN, OF RUTLAND, VERMONT, ASSIGNOR TO HOWE SCALE COMPANY, OF RUTLAND, VERMONT, A CORPORATION OF VERMONT.

PIVOT FOR SCALE LEVERS.

Application filed September 3, 1921. Serial No. 498,320.

To all whom it may concern:

Be it known that I, HUGO F. BRUGMANN, a citizen of the United States, residing in Rutland, county of Rutland, and State of Vermont, have invented certain new and useful Improvements in Pivots for Scale Levers, of which the following is a specification.

In the construction of scale levers, particularly such as are employed in the manufacture of railroad track scales and scales for other heavy work, considerable difficulty is encountered in accurately locating the pivots which must be in exact location upon the scale lever and parallel with and at proper distances from other pivots carried by the scale lever. The working edge of a pivot must be in a horizontal position and exactly parallel and on a common level with every other pivot in the same member.

The object of the present invention is to provide improved scale lever pivots which can be adjustably mounted in machined holes in the scale levers so that the pivots will be interchangeable and standardized, and more readily and accurately applied and removable for repair or renewal.

The master locations of the scale lever pivots are obtained by boring holes in the scale levers at properly spaced points determined by means of the micrometer screw adjustments on the tables of the boring machine. A pivot holder is channeled to receive a hardened, finished pivot bar and then accurately turned into cylindrical form to fit the bored holes of the scale lever. In shaping the cylindrical surface of the pivot holder, the unfinished holder block is mounted to turn upon an axis parallel with the working edge of the finished pivot, which is conveniently accomplished by mounting it upon the finished pivot or upon a master pivot or mandrel of the same shape as the finished pivot and then turning the assembled pivot and holder upon centers in the pivot axis parallel with the working edge.

The pivot holder is made expandable and wedging means are provided between the holder and pivot bar so that, when the holder and pivot are mounted and properly adjusted in the machined hole of the scale lever, the holder can be expanded into bind-

ing engagement with the scale lever by the action of the wedging means. The wedging means comprise preferably cooperating faces upon the pivot bar and holder, which are tapered or inclined to the working edge or longitudinal axis of the pivot proper, whereby the holder is expanded by forcing the pivot longitudinally into it.

In order that my invention may be fully understood, I will first describe the same with reference to the accompanying drawings and afterward point out the novel features in the annexed claims. In said drawings:

Figure 1 is an inside elevation of one part of a sectional pivot holder.

Figure 2 is an end view of the same.

Figure 3 is a side elevation of the finished pivot bar.

Figure 4 is an end view of the same.

Figure 5 is a sectional, plan view of a portion of a scale lever having the improved removable pivot mounted therein.

Figure 6 is a side elevation of the same showing the pivot in end elevation.

Figure 7 is a vertical, transverse section of the same taken on the line 7-7 of Figure 6.

Figure 8 is a view of the combined pivot and holder showing in section the holder in the form of Figure 9.

Figures 9, 10, and 11 are, respectively, end views of different forms of the improved pivot and holder.

Figures 12 and 13 are detail perspective views of parts of different forms of scale levers, illustrating the mounting of the improved pivot in a double web affording support at opposite ends and exposing the pivot between its ends.

Figure 14 is a side elevation of the form of pivot and holder shown in Figures 12 and 13.

Figure 15 is an end view of the same.

Figure 16 is a side elevation of a slightly different shape of pivot and holder for use with the double webbed scale lever.

Figure 17 is an end view of the same.

In Figures 5, 6, and 7, I have shown a section or portion of a well known type of straight lever for a railroad track scale. The lever is indicated at 1 and is formed as usual with a main body portion having the

strengthening ribs or flanges above and below as shown at 1^a and 1^b and provided at approximately the proper locations for the pivot bearings with integral cast hubs or bosses 2 extending upon opposite faces of the main web body of the scale lever.

In the proper boring machine, with the positions located as accurately as possible, suitable holes or sockets are bored transversely through the reinforced hubs or bosses of the levers where the pivots are to be located. The cylindrical holes referred to are indicated in Figures 5, 6, and 7 by numeral 5. When these holes, as shown at 15 5, are drilled, the proper parts of the strengthening bosses 2 are cut away to expose the pivots where desired. In the form of lever shown in the figures referred to, these bosses 2 are cut away as shown at 3, 20 because, in this form of scale lever, the working edge of the pivot is exposed on opposite sides of the scale lever, and presented upwardly.

A finished, hardened pivot bar 10, such as 25 shown in Figures 3 and 4, is formed with a knife edge bearing 10^a of the desired included angle. In machining this pivot bar 10, the bar is supported upon centers in its longitudinal axis and the faces 10^b are cut 30 parallel with this longitudinal axis with the result that the knife edge will also be parallel to the axis of the bar. The bottom of the bar 10 is then formed by cutting the faces 10^c upon a taper or inclination to the 35 axis of the bar. The result of this operation is the production of a pivot bar that is of smaller cross sectional area at one end than at the other and with an even taper from the large end to the small end while, at the 40 same time, the knife edge bearing is truly parallel to the longitudinal axis of the bar.

To adjustably and removably mount the 45 improved pivot bar in the machined hole of the scale lever, I form an expandable pivot holder which may be variously constructed as hereinafter explained, but which is preferably made in sections channeled to receive the pivot bar and externally shaped to accurately fit the machined opening in the 50 scale lever.

The preferred form of the expandable pivot holder as illustrated in Figures 1, 2, 55 5, 6 and 7 of the drawings, comprises two complementary halves or sections 15, having faces 17 in the plane of separation of the sections and the faces 18 and 19, the former of which is in a plane parallel with the longitudinal axis of the holder while the latter is at an angle or upon a taper to said axis. The angular relation of the faces 18 and 60 19 is, of course, determined by the angular relation of the faces 10^b and 10^c of the pivot bar above referred to.

Two holder sections, made in exact duplicates, 65 are fitted over the pivot bar 10, or a

master pivot or mandrel of the same shape, and clamped in position thereon and placed in a lathe upon the centers in the longitudinal axis of the pivot bar parallel with the working bearing edge 10^a. Supported in this manner, the exterior surface of the sectional holder block is turned down to a cylindrical form to accurately fit the cylindrical hole 5 machined in the scale lever as hereinbefore described.

When the sectional holder has been shaped to fit the hole in the scale lever, it has portions cut away, as indicated at 20 corresponding with the cut-away portions of the reinforcing bosses 2 of the scale lever so that, when the assembled pivot bar and holder are driven in place in the hole of the scale lever, the working knife edge of the pivot bar will be exposed where desired.

When the improved pivot is mounted in the prepared hole of a scale lever, its position is accurately adjusted by rotating the pivot and holder in the hole or socket of the lever. In making this adjustment, the holder can be slightly wedged into binding position 90 so that the holder and pivot bar will not turn too readily. The shape of the projecting end of the pivot bar affords means for convenient engagement for the proper tool by which the final adjustment can be made. When the knife edge bearing of the pivot is 95 in the desired location with reference to the other pivots of the system of scale levers, the pivot bar is driven up tight in its holder to expand the holder into firm binding engagement with the socket of the scale lever.

It will be understood that, in assembling a pivot bar in its expandable holder the surfaces 10^b of the pivot come in contact with the surfaces 18 of the sectional holder while the surfaces 10^c of the pivot are in contact with the surfaces 19 of the holder. This insures the presentation of the knife edge bearing 10^a of the pivot in proper horizontal position. The tapered surfaces of the pivot and holder cause the holder to expand when the pivot is driven longitudinally in the channel of the holder and in expanding the holder into this fixed position, the accurate horizontal position of the knife edge bearing will be maintained.

Figure 10 of the drawings, I have shown a slight modification in which the pivot holder 30 is formed of a single piece of metal with a pivot-receiving channel having angular side walls 31 parallel with the longitudinal axis of the pivot holder and a side wall 32, which is tapered or inclined to said axis. The holder 30 is cut longitudinally at 33 to form expandable spring jaws of its two sides. 35 is a pivot bar shaped to fit the channel of the holder 30, the knife edge bearing 35^a of this bar being presented in the vertical plane of the cut 33 and exposed at opposite ends by the cut-away portions of 130

the holder 30, as in the preferred form above described. It will be understood that, in this form of holder and pivot bar, the bottom wall of the pivot bar is tapered to correspond 5 with the tapered surface 32 of the holder.

In Figure 11, I have shown a further modification, in which the holder 40, made of a single piece of metal, has a channel or socket 41, the cross section of which is partly circular and partly angular and the opposite ends of the socket being of different diameters so that the surface walls taper or incline to the longitudinal axis. In this form of the device, the pivot bar 45 is shaped 10 to accurately fit the channel of the holder 40 with its surfaces tapering from one end to the other and having its angular knife edge bearing 45^a presented in a plane parallel with its longitudinal axis. In this 15 form, the holder 40 has a longitudinal cut 42 to present the two sides of the holder as expandable jaws which are forced outwardly into engagement with the hole in the scale lever when the pivot is driven into place.

Figures 8 and 9 show a form of pivot bar 10 shaped exactly like that shown in Figures 3 to 7, and an expandible holder 15^a fitting said pivot bar but made in a single piece of metal.

In Figures 12 to 17 inclusive, I have shown a further slight modification of the improved removable pivot bearing for scale levers, in which the pivots are mounted in double webbed portions of levers with their 30 ends inclosed in the supporting lever walls and their bearings exposed between their supported ends. Figures 12 and 13 show parts of scale levers of the type generally referred to as "pipe lever scales". Figure 12 shows an end of one of such scale levers, in which the casting 50 has two reinforced webs 51, through which are bored the cylindrical openings 52 to receive the pivot holders 53 supporting pivot bars 54. In 35 Figure 13, I have shown a section of another portion of such a scale lever, in which the webs 60, joined by the reinforcing integral boss 61, have bored through their reinforced portions a hole 62, in which is seated the expandible pivot holder 63, carrying the pivot bar 64. In each of these illustrations in Figures 12 and 13, the knife edge bearings of the pivot bars are exposed 40 between the web portions 50 or 60 and, in Figure 12, such pivot bars are shown presented both upwardly and downwardly, showing that it is simple to place the pivot bearings in any desired position in any form 45 of scale lever. The form of holder and pivot bar illustrated in Figures 12 and 13 is more clearly shown in the detail Figures, 14 and 15. This pivot bar and holder of Figures 14 and 15 is of the same construction as that illustrated in the modified form of Figure 50 10 above described, with the exception that

a portion of the holder 53 is cut away to expose the knife edge bearing between the ends of the holders, as indicated at 55.

In Figures 16 and 17, I have shown a pivot bar and holder with a centrally disposed bearing of the same general type as just described, in which the channel of the holder 70 and the shape of the pivot bar 71 are substantially the same as shown in Figures 6, 7, 8, and 9 of the drawings. 75

The inside surfaces of the holder are the same taper and angles as the outside surfaces of the pivot and come in contact over the whole surface. One advantage of having the pivot holder in two pieces is that it can be readily and economically machined on the channel surfaces which come in contact with the pivot. This is necessary because, unless these contiguous surfaces are machined, the pivot may not bear the entire length of its support, which would result in a deflection, which would impair the accuracy of the lever and might result in breakage of the pivot. Furthermore, the fact that the inside surfaces are machined 85 gives a better frictional contact to hold the pivot in place when it is driven home, for the reason that the smoother the surface, the greater the co-efficient of friction. 90

Pivot bearings constructed in accordance 95 with this invention are removable, adjustable and interchangeable. The construction and method of making are important from a manufacturing standpoint in view of the fact that the pivots and holders can be 100 manufactured in quantity in readiness for mounting in the desired scale levers. The convenience for accurately adjusting the bearings after mounting and the facilities with which parts may be removed for repair are of great practical importance. The pivot holders are preferably made of some suitable, non-corrosive metal to facilitate removal after long usage and exposure but the invention is, of course, not limited to 105 its use with any particular material. 110

This form of knife edge bearing is important for nearly all classes of scale work in which the construction necessitates the accurate arrangement of knife edge bearings with relation to the levers and each other. It is particularly important, however, in the construction of heavy scales, such as used for railway work, in that it affords convenient means for accurately 115 mounting the scale pivots and for adjusting their relation and repairing parts in case of accident or wear, such heavy scales being more or less permanently installed in underground vaults, with a platform covering, which it has heretofore been necessary to remove for the purpose of taking the scale levers out of the vault and sending them to a repair shop for the purpose of mounting 120 new knife edge pivot bearings. 125

It has been found that when the improved pivot is driven up to a practical degree of tightness in the scale lever, the knife edge of the pivot is held in fixed relation to the lever, but that it is possible, by driving up the pivot a bit tighter, to slightly raise the knife edge in the pivot holder. It has been found by experiment with the preferred form of pivot as illustrated in Figures 5, 6, 10 and 7 of the drawings that from the point of beginning to drive in the pivot in the holder to the point where the pivot was considered as "driven home", the knife edge of the pivot was actually raised .009". This slight change in elevation of the knife edge between extremes in the driven-in condition of the pivot permits some latitude of practical importance in determining the final adjustment of the pivot in the scale lever. It will, of course, be understood that, in designing a scale lever, the position of the holes in the lever should be arranged with regard to the stated variations so that the knife edges can be placed within practical limits of where they are wanted.

I claim:—

1. A machined-in pivot for scale levers comprising an expansible pivot holder adapted to be seated in a socket of a scale lever, and a pivot bar seated in said holder and formed with faces which are respectively parallel with and inclined to the longitudinal axis of the pivot bar, whereby the pivot bar forces the holder into binding engagement with the socket of the scale lever and maintains its working edge in fixed relation to the scale lever.

2. A removable pivot for scale levers comprising an expansible socketed holder adapted to fit a hole in a scale lever, and a pivot bar fitting the socket of said holder, said holder and pivot bar being formed with corresponding engaging surfaces parallel with the longitudinal axis of the pivot bar and other engaging surfaces which are inclined to said axis.

3. The combination with an expansible pivot holder formed with a receiving socket, one face of which is parallel with the longitudinal axis of the holder while another face is tapered or inclined to said axis, of a knife edge pivot bar having a surface parallel with its longitudinal axis and another surface inclined to its said axis.

4. The combination with an expansible socketed pivot holder formed in complementary sections, a knife edge pivot bar fitting the socket of said sectional holder, corresponding engaging faces of the holder and pivot bar being inclined to the axis of the bar to cause the holder to expand when the bar is forced therein.

5. The combination with a scale lever having a substantially cylindrical machined pivot-receiving socket, of an expansible

socketed pivot holder shaped to fit and be adjusted in the socket of said scale lever, and a longitudinally tapered pivot bar seated in said holder.

6. The combination with a scale lever 70 having a machined pivot-receiving socket, of an expansible pivot holder adapted to be seated in the socket of said scale lever, and a pivot bar seated in said holder and formed with faces which are respectively parallel 75 with and inclined to the longitudinal axis of the pivot bar, whereby the holder is expanded into binding engagement with the socket of the scale lever and the working edge of the pivot bar is maintained in the 80 desired angular relation to said lever.

7. The combination with a scale lever having a machined pivot-receiving socket, of an adjustable expansible pivot holder formed with a longitudinally tapered socket, 85 and a longitudinally tapered knife edge pivot bar fitting the socket of said holder.

8. The combination with a scale lever having a cylindrical pivot-receiving socket of an expansible pivot holder shaped to fit and 90 be adjusted in said lever socket and formed with a longitudinally tapered socket, and a knife edge pivot bar tapered longitudinally to fit the socket of said holder.

9. The combination with a scale lever having a reinforced section formed with a machined pivot-receiving socket, of an expansible socketed holder adjustably mounted in the socket of said scale lever, and a longitudinally tapered pivot bar fitting the 100 socket of said holder.

10. A removable pivot for scale levers comprising an expansible socketed holder adapted to fit a hole in a scale lever, and a knife-edge pivot bar fitting the socket of 105 said holder, said holder and pivot bar being formed with corresponding engaging surfaces inclined to the longitudinal axis of the pivot bar and the holder being cut away to expose the working knife edge where desired.

11. The combination with a reinforced scale lever formed with a pivot-receiving socket in its reinforced part and having said reinforced part cut away sufficiently to expose the working pivot, of an expansible socketed holder mounted in the socket of said scale lever and cut away to expose the working pivot, and a pivot bar wedged in the socket of said holder.

12. The combination with a scale lever formed with a pivot-receiving socket, an expansible socketed pivot-holder rotatably adjustable in said lever-socket, a pivot bar mounted in the socket of said holder and projecting beyond the holder at one end, said holder and pivot bar having engaging surfaces which permit relative longitudinal movement and lock circumferentially, whereby the pivot and holder can be rotated 130

together in the lever socket to adjust the pivot bar by engaging the projecting end of said bar.

13. The combination with a scale lever formed with a pivot-receiving socket, an expandible socketed pivot-holder rotatably adjustable in said lever-socket, and a pivot bar wedged longitudinally in the socket of said holder, the engaging surfaces of said holder and pivot bar permitting a limited relative movement longitudinally and locking circumferentially.

14. In a device of the character described, the combination of a member having a socket, a pivot holder rotatably adjustable in said socket, and a pivot bar wedged longitudinally in said holder, and wedging means securing both the holder and pivot bar in position.

15. In a device of the character described, the combination of a member having a socket, an expandible pivot holder rotatably adjustable in said socket, a pivot bar longitudinally wedged in said holder, and locking the holder and bar in position.

16. In a device of the character described, the combination of a shaped pivot bar having longitudinal wedge surfaces, with a pivot holder having a longitudinally tapered channel to receive said pivot bar, and formed with an outer cylindrical surface parallel with the working bearing of said pivot bar.

17. In a device of the character described, the combination of a member having a socket, a longitudinally tapered pivot bar having a working bearing, with a holder rotatably adjustable in said socket, said holder being channeled to receive said tapered pivot bar, and formed with an outer cylindrical surface parallel with the working bearing of said pivot bar.

18. In a device of the character described, the combination of a knife edge pivot bar having its knife edge parallel to its longitudinal axis and its cross-sectional area smaller at one end than at the other, with a holder block formed with a receiving channel to accurately fit said pivot bar, and an outer cylindrical surface parallel with the knife edge of said pivot bar.

19. In a device of the character described, the combination of a tapered pivot bar formed with a knife edge parallel with its longitudinal axis, with a sectional pivot holder, each section of which is formed with an angular channel in its inner face, one wall of each of said channels being parallel with the axis of the holder section while the other wall of each channel is longitudinally inclined to said axis, said sectional pivot holder being formed with an external cylindrical surface, which is parallel to the knife edge of said pivot bar.

HUGO F. BRUGMANN.
